UNITED STATES PATENT OFFICE.

CLARENCE M. EVELETH, OF RIVER FOREST, ILLINOIS.

OIL CAN.

1,411,775.

Specification of Letters Patent. Patented Apr. 4, 1922.

Application filed May 5, 1921. Serial No. 466,963.

To all whom it may concern:

Be it known that I, CLARENCE M. EVELETH, a citizen of the United States, residing at River Forest, in the county of Cook and 5 State of Illinois, have invented a new and useful Oil Can, of which the following is a specification.

This invention relates to oil cans, its object being to provide a can with means for 10 catching oil dripping from the spout and which would otherwise be lost.

A further object is to provide a means for draining the oil back into the can, there being a valve arrangement for automatically 15 closing the drain opening when the can is tilted in any direction during the discharge of oil.

Another object is to provide a device of 20 this character which is simple, compact and efficient and will not readily get out of order.

With the foregoing and other objects in view which will appear as the description proceeds, the invention resides in the combination and arrangement of parts and in 25 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a section through a portion of 35 a can having the present improvements.

Figure 2 is a detail view of the blank from which is formed the spout holding disk and the valve bracket.

Referring to the figures by characters 40 of reference 1 designates a portion of the body of an oil can, the mouth 2 thereof being surrounded by a screw threaded flange 3 engaged by a screw cap 4. This screw cap has a central tubular portion 5 one end of 45 which projects beyond the cap and is screw threaded as shown at 6. A supplemental cap 7 engages this threaded portion 6 and has a central opening 8 surrounded by a depending circular flange 9. An inclined 50 disk 10 is secured within the central tubular portion 5 and has a central opening 11 and a small drain opening 12. This disk is formed in a blank including a neck 13 and an arm 14 and before the disk is placed 55 within the tubular portion 5 and soldered at its edges the neck 13 is bent downwardly

as shown in Figure 1 and the arm 14 is bent to form a laterally extending yoke 15 having a large guide opening 16 in the upper portion thereof and a small guide opening 17 directly thereunder. The centers of these openings 16 and 17 are in line with the center of the opening 12. A delivery nozzle 18 is secured at its base within the opening 11 and extends through the opening 8 in 60 the cap 7. A cylindrical valve 19 is slideable within the opening 16 and has a conical end 20 which projects into the opening 12 so that the valve is thus held against displacement relative to the two openings. The 65 lower end of the valve 19 rests loosely on the flat base of an inverted conical lifting cam 21 which is supported by the lower portion of the yoke 15 and has a stem 22 extending downwardly therefrom and carrying a weight 23. Thus it will be seen that 70 when the can is in its normal or upright position any oil draining along the outer surface of the nozzle 18 will flow into the receiving compartment 24 formed within the 75 tubular portion 5 above the disk 10 and will then drain through the opening 12 back into the can body 1. When the can is tilted in any direction, however, for the purpose of directing oil through the nozzle the 80 weight 23 will cause the cam 21 to tilt or move relative to the valve 19 so as to shift the valve longitudinally and cause it to close the opening 12. Thus no oil can flow 85 from the can by way of the opening 12 and any oil that may be within the compartment 24 will be trapped therein by the flange 9 on the cap 7.

By providing an oil can with an improvement such as described a considerable saving 90 of oil will be effected and, furthermore, the outer surface of the can will be kept free of oil and oil will be kept off of the hands of the user.

It will be seen that the parts can be easily 100 made and assembled and the entire structure can be very cheaply made by stamping and soldering.

What is claimed is:—

1. The combination with an oil can, of 105 a cap removably mounted thereon, a central compartment within the cap having an inclined bottom provided with a drain opening, a nozzle supported by said inclined bottom and extending beyond the cap, a 110 slide valve supported under the bottom of said compartment and normally projecting

- into the drain opening, and gravity operated means for shifting the valve to closed position when the can is tilted in any direction away from its upright position.
- 5 2. The combination with an oil can of a cap having a compartment provided with an inclined bottom, there being a drain opening in said bottom, a delivery nozzle extending from said bottom, a valve slidably supported below the bottom of said compartment, a cam supporting the valve, and gravity controlled means for operating the cam to seat the valve and close the drain opening when the can is tilted in any direction away from its upright position.
- 10 3. The combination with an oil can, of a cap having a compartment therein provided with an inclined bottom, there being a drain opening in said bottom, a delivery nozzle extending from and supported by said bottom, a supplemental cap engaging the wall of said compartment, an inwardly extending flange thereon surrounding and spaced from the nozzle, and gravity operated means for closing the drain opening when the can is
- 15 20 25

tilted in any direction away from its upright position.

4. The combination with an oil can, of a cap having a compartment therein, a disk secured in the compartment and constituting an inclined bottom therefor, said disk having a drain opening, a nozzle supported by the disk, an arm integral with and depending from the disk and forming a guide yoke, a valve slidably engaging the yoke, a cam supported by the yoke and constituting a support for the valve and a weighted stem depending from the cam, said cam constituting means for shifting the valve to close the drain opening when the can is tilted in any direction away from its upright position.

In testimony that I claim the foregoing as my own, I have hereto affixed my signature in the presence of two witnesses.

CLARENCE M. EVELETH.
